UNITED STATES PATENT OFFICE

2,449,932

METHOD OF THAWING MATERIALS

John W. Forsythe, deceased, late of Wilkinsburg, Pa., by Mary Alice Forsythe, executrix, Wilkinsburg, Pa., and Edward J. Smotzer, Pittsburgh, Pa., assignors to Carnegie-Illinois Steel Corporation, a corporation of New Jersey

Application January 24, 1945, Serial No. 574,436

1 Claim. (Cl. 34—30)

1
This invention relates to a method of heating materials; more particularly it relates to a method of thawing materials in containers such as cars and the like.

One of the objects of the invention is the provision of a method for thawing materials in containers to allow their discharge therefrom. This and further objects of the invention will become apparent as the description proceeds.

Materials such as ore, limestone, coke, and coal, as well as other similar materials produced or occurring in broken or granular form are transported most economically in open railroad cars and the like from which they are discharged at the point of use or storage, either from bottom openings in the cars or by means of car dumpers which invert the entire car. Such discharge of materials is rendered difficult in cold weather by reason of freezing of the materials in the cars in transit or while standing in the yard due to rain, snow, and ice falling on them. The problem of discharge of the cars is most serious where the material is shipped from lake ports where it is subjected to the damp atmosphere prevailing in such localities.

Various expedients have been tried in the past to thaw and loosen the frozen materials in the cars sufficiently to permit their ready discharge therefrom. Such methods have included the building of wood fires under the cars, the holding of gas jets against the sides of the cars in various places, and the use of steam baths to which parts of the car or the whole car have been subjected. The first two methods are obviously crude and hit-or-miss. Besides requiring a considerable amount of time, they are further open to the very serious objection that they subject portions of the car to sufficiently high temperatures to damage the paint thereon, and even to buckle and otherwise seriously weaken the sides and frames of the cars. Steam baths are also slow and do not in the main impart sufficient heat to the car and its contents to insure thorough thawing of the material. Furthermore, because of the moisture contained in the steam, icing of the apparatus at the thawing station, particularly in very cold weather, inevitably results.

By use of the method of the present invention, the difficulties above outlined attendant upon the use of prior thawing methods are overcome. Briefly, the invention provides means for completely enclosing one or more material carrying devices, such as railroad cars, and for subjecting such cars in the initial portion of the heating cycle to a moderately high temperature

which may be, for example, on the order of 750° F., following which the heat is cut back and the car and its contents allowed to soak in the latter part of the cycle at a lower temperature, which 5 may be, for example, on the order of 250° F. Upon completion of the thawing cycle, the container, which may be, for example, a railroad car, is transferred to the discharge station, which may be a car dumper, whereupon additional cars are 10 charged into the thawing chamber or enclosure and the thawing cycle repeated. In the preferred embodiment of the apparatus described in the following disclosure for purposes of illustration, the operation of the heating means and of various protective devices are made automatically responsive to the travel of the thawing chamber closure means whereby a minimum of manual control is required of the operator.

The invention will be more fully understood by 20 reference to the accompanying drawings, in which:

Figure 1 is a side elevation, partially in section, of the thawing chamber; and

Figure 2 is a view in cross section of the thawing chamber taken along the line II—II of Figure 1.

The thawing building shown in Figures 1 and 2, which may be of brick or other heat-resistant material, is designated generally by the reference 30 character 1. Building 1 consists of a foundation 2, the upper surface of which lies at ground level. The building is provided with ends 3 closing the upper portions thereof, and with two doors 4 and 5, door 4 to the left of Figure 1 being sometimes referred to as door #1, and door 5 to the right in Figure 1 being sometimes referred to as door #2. The doors are each provided with a hoisting mechanism, whereby they are lifted sufficiently to allow railroad cars to enter and leave the 40 chamber, the hoisting mechanism for door 4 comprising top sheaves 6 and lowering and hoisting drum 8, the corresponding parts of a similar hoisting mechanism for door 5 being designated 7 and 9, respectively.

45 The lower portion of the thawing building is completed by side walls 10 and 11 and by ceiling 12 which forms a floor for the upper portion of the structure. The upper portion of the structure 1, which houses the gas heating and circulating means subsequently to be described, is provided with sides 13 and roof 15, as shown in Figures 1 and 2.

The lower or thawing chamber of the structure is made wide enough, in the particular embodiment shown, to receive a standard railroad car

17, on tracks 16, and a narrow gauge electric pusher locomotive 18, on tracks 18, side by side. Locomotive 18 is provided with a retractable side pusher arm (not shown) which may be advanced to engage the rear of the car to be moved. Such design has been found to lend flexibility to the layout, since the narrow gauge locomotive is not impeded in its travel by the railroad cars, but may proceed to pick up as many or as few cars as are desired. In addition, the space above the narrow gauge track is useful as a walkway when the locomotive is removed and the thawing apparatus is not in use. It is to be understood, however, that other means for moving the cars into and through the thawing device may be employed if desired. Locomotive 18, which is of less height than the cars 17, runs under overhanging portion 20 of the chamber, which forms a portion of the return air flue, which will be subsequently described.

The heating of the air by which thawing of the material is accomplished is performed by two similar heating devices 21, located on the floor of the upper portion of the structure. The left-hand heating device 21 in Figure 1 will sometimes be referred to as unit No. 1, and the right-hand device will be referred to as unit No. 2. Each such heating device 21 comprises a combustion chamber 22, into which is directed the flame from oil burner 23. Such burner is provided, as shown in Figures 1 and 4, with an oil supply pipe 24, a steam pipe 25 for supplying steam for atomizing the oil, and a combustion air blower 26 driven by motor 28 for delivering air to the burner through delivery pipe 29. The products of combustion travel longitudinally of combustion chamber 22 upwardly through opening 27 in the rear thereof into mixing chamber 28 where they are intimately admixed with recirculated air from the lower thawing chamber of the apparatus. Such recirculated air travels upwardly from the thawing chamber through uptakes or flues 29 (see Figure 2), laterally into passage 30, upwardly and then laterally through passages 31 and then upwardly through passages 32, from which it emerges into the mixing chamber.

Circulating air fan 33, driven by motor 34, draws the mixture of recirculated air and products of combustion from mixing chamber 28 into the housing 35 in which the fan is located, and then discharges it under pressure into discharge duct 36. Each fan 33 is provided with a damper 37 in the discharge pipe thereof, whereby, in the event of failure of one heating device 21 or of any of its attendant parts it may be closed off from duct 36 and the entire heating burden borne by the other heating device.

Discharge ducts 36 are connected to ducts 38, which extend longitudinally of the ceiling of the thawing device, as shown in Figures 1 and 2. Vertical discharge pipes 39 and 40, pipes 39 being on the right-hand side of Figure 2 and pipes 40 being on the left-hand side, are connected to longitudinal ducts 38 at substantially uniform spaced points. The thawing chamber shown is designed to take two standard ninety-ton ore cars coupled end to end. It is for this reason that there is a slightly greater space between the adjacent vertical pipes at the longitudinal center of the chamber, that is, the position of the coupling between cars, than between those elsewhere. Pipes 39, which run only to the top of overhang 20, are each provided with an upper nozzle 41 and a lower nozzle 42, discharging the

heated air to the contents of the car, and down the side of the car, respectively. Pipes 40 are provided with upper nozzles 43, which discharge the heated air against the other side of the car. Each pipe 40 is also provided with lower nozzles, alternate pipes having lower nozzles 45 which discharge the heated gas horizontally under the car, and the other pipes 40 having lower nozzles 44 which discharge the gas upwardly at an angle against the side of the car. Each nozzle is provided with its own independent damper 46, of which one is shown in Figure 2 in conjunction with nozzle 43, to control the delivery of gas therefrom, and each nozzle is preferably made of a fish tail shape to provide a heated gas jet having a broad coverage over the surface of the car and its contents.

When using the particular apparatus above described, in the thawing of two ninety-ton ore cars at one time, it has been found that, with heating devices 21 with a rated capacity of 10 million B. t. u. per hour each, a ten-minute preliminary heating period of 500-700° F., followed a cut-back to soaking at 200-250° F. for from 5 to 20 minutes is sufficient to thaw most if not all cars encountered during ordinary winter weather, to an extent sufficient to allow their being emptied in a satisfactory manner by a car dumper which inverts the cars. It is usually necessary to thaw the material to a depth of only about one inch from the car walls and bottom to accomplish the desired freeing of the material from the car. Under exceptionally severe freezing conditions it may be necessary to increase either the length of the preliminary high temperature heating period or the soaking period, or both, and for light freezing conditions either or both heating periods may be shortened. Within the scope of the method of the present invention there may be employed, therefore, a preliminary heating at from 500° to 750° F. for from 5 to 15 minutes, and a subsequent heating at from 200° to 250° F. for from 5 to 20 minutes.

Preferably an automatic control system is provided by which the thawing temperatures are maintained at the prescribed values for the prescribed periods. The details of this system are not described for the reason that they are fully disclosed and claimed in our co-pending application Serial No. 609,639, filed August 8, 1945, as a division of the present application.

Use of the method of the present invention has been found to overcome a serious bottleneck in the handling of ore, limestone, and coke in the winter time. In addition to the speed and certainty with which such materials may now be dumped after the thawing by such device, it has been found that no injury results to the cars by reason of such heating. The metal work, paint, rubber air hoses, and rubber hose gaskets show no deterioration resulting from such treatment, which is in marked contrast to the damage caused by the previous use of wood fires or gas jets in thawing the cars.

Whereas a particular method of thawing has been described for purposes of illustration, it is obvious that numerous variations within the teaching of the invention are obvious to one skilled in the art. The scope of the invention is therefore defined by the appended claim.

We claim:

A method of thawing frozen materials in railroad cars comprising subjecting a car situated in an enclosed thawing chamber to a plurality of

blasts of a gaseous blend of air and products of combustion at a temperature of 500° to 750° F., continuously removing the blast gases from the chamber, blending a portion of the gases thus removed with additional air and products of combustion, continuously recirculating the resulting blend of gases to the blasts at this temperature for 5 to 15 minutes; and thereafter subjecting the car to a plurality of similarly constituted blasts at a temperature of 200° to 250° F. for a period of 5 to 20 minutes.

MARY ALICE FORSYTHE,
Executrix of the Estate of John W. Forsythe,
Deceased.

EDWARD J. SMOTZER.
